UNITED STATES PATENT OFFICE.

JOHN McBRIDE, OF MCKEE'S ROCKS, PENNSYLVANIA.

LUBRICATOR FOR PUMP OR PISTON RODS.

SPECIFICATION forming part of Letters Patent No. 661,317, dated November 6, 1900.

Application filed March 12, 1900. Serial No. 8,304. (No model.)

To all whom it may concern:

Be it known that I, JOHN McBRIDE, a citizen of the United States of America, residing at McKee's Rocks, in the county of Allegheny and State of Pennsylvania, have invented certain new and useful Improvements in Lubricators for Air-Brake and other Pumps or Piston - Rods, of which the following is a specification, reference being had therein to the accompanying drawings.

This invention relates to certain new and useful improvements in lubricating devices adapted for use upon piston-rods of air-brake cylinders and pumps of all descriptions.

One object of the invention is to construct a lubricating device which is adapted to be arranged upon a piston-rod in such a manner as to lubricate the same and to further engage the fastening-nuts for the gland to prevent their turning, thereby preventing the gland from becoming loosened during the operation of the piston - rod; furthermore, in providing a suitable lubricating-supply for keeping the device saturated at all times with a lubricant.

A further object of the invention is to construct a lubricating device which will be extremely simple in construction, strong, durable, efficient in its use, and comparatively inexpensive to manufacture.

Briefly described, the invention consists of bending a suitable piece of wire in a manner to form a pair of circular-shaped clasping-yokes and covering the same with a suitable fibrous packing, forming a concentric lubricating device, which is adapted to be saturated with a suitable lubricating material when the device is in position upon a piston-rod. I also provide a suitable lubricating-supply for keeping the device saturated with a lubricant at all times.

With the above and other objects in view the invention finally consists in the novel construction, combination, and arrangement of parts to be hereinafter more fully described, and specifically pointed out in the claims.

In describing the invention in detail reference is had to the accompanying drawings, forming a part of this specification, and wherein like numerals of reference indicate

corresponding parts throughout the several views, in which—

Figure 1 is a side elevation showing my improved lubricating device in position upon a piston-rod and engaging the securing-nuts of the gland. Fig. 2 is a cross-sectional view taken on the line 2 2 of Fig. 1. Fig. 3 is a vertical sectional view of the lubricating device. Fig. 4 is a perspective view of the pair of spring clasping-yokes.

Referring to the drawings by reference-numerals, 1 indicates the gland upon the bolts 2 and secured in position by means of nuts 3.

4 indicates a lubricating-supply supported in any manner desired, and 5 denotes the piston-rod.

The reference-numerals 6 7 denote a pair of circular-shaped spring clasping-yokes formed by bending a suitable piece of wire in the manner shown, the top of each yoke bent at an angle, as at 8 9, forming projections in order to permit of the gripping of the same when it is desired to remove the lubricating device. The spring clasping-yokes 6 7 are entirely covered by a suitable fibrous packing 10, which is adapted to be saturated with a lubricating material and placed in position upon a piston-rod and, further, adapted to engage the fastening-nuts of the gland to prevent their turning, thereby overcoming any accidental loosening of the gland. The material of which the fibrous packing is composed is made up in an oblong form, so as to cause the same to follow any irregularities in the diameter of the piston-rod and preserve a close contact with the surface of the same, so that the lubricating material will engage the piston-rod at all times. The fibrous packing is of such thickness that when the device is mounted upon a piston-rod, as shown in Fig. 2, the action of the spring-yokes will cause the device to always be in engagement with the securing-nuts of the gland to prevent their turning and to further have the same at all times in engagement with the piston-rod. Of course it will be evident that the packing will be lubricated at all times by the supply 4.

It is thought that the many advantages of my improved lubricating device can be read-

ily understood from the foregoing description, taken in connection with the accompanying drawings, and it will be noted that various changes may be made in the details 5 of construction without departing from the general spirit of my invention.

Having thus fully described my invention, what I claim as new, and desire to secure by Letters Patent, is—

- 10 1. A lubricating device comprising in its construction a pair of substantially circular-shaped spring clasping-yokes, and a fibrous packing entirely covering the said yokes.
- 15 2. A lubricating device consisting of a suitable piece of spring-wire bent to form a

pair of spring clasping-yokes connected together and suitably surrounded by a fibrous packing.

3. In a lubricating device for piston-rods and the like, a piece of spring-wire bent to 20 form a pair of substantially circular-shaped spring-yokes in alinement with each other, and a fibrous packing surrounding the said yokes.

In testimony whereof I affix my signature 25 in the presence of two witnesses.

JOHN McBRIDE.
